DEVICE FOR POLISHING LOCOMOTIVE CRANKPINS

Henry E. Klinglesmith, Los Angeles, Calif.

Application August 24, 1943, Serial No. 499,765

21 Claims. (Cl. 51—241)

This invention relates to a device for polishing locomotive crank pins.

After locomotive crank pins have been cut or machined by a crank pin cutting or turning machine, regardless of the condition of the machine or of the skill of the operator, the bearing surface of the pin is left in a roughened condition. Hence it is necessary, in order to prepare the crank pin for satisfactory use, to follow the machining thereof with a polishing and smoothing operation in order to remove all high spots and irregularities and cause the pin to have a uniform bearing surface.

Heretofore it has been common practice, after the machining of the crank pin has been completed, to follow this by hand filing and hand polishing. Such manually performed efforts have required a great deal of time and have not resulted in furnishing the crank pins with satisfactory bearing surfaces.

It is the purpose of this invention to provide an improved means for mechanically performing the above mentioned polishing and smoothing operation.

More specifically speaking, among the objects of the invention are: to provide an improved mechanically driven polishing device whereby the polishing elements are supported in a properly tensioned, more readily adjustable manner; to provide rotatable polishing means which will, in a more satisfactory manner, automatically accommodate itself to surface irregularities of the crank pin being polished; to provide a simplified mounting means for the polishing means; and, in particular, to provide an improved means for replaceably securing strips of abrasive material to a rotary support or carrier, in a position to efficiently perform the polishing operation.

Additional specific important objects of the invention are: to provide an improved means, attachable to the crank pin to be polished, to rotatably support the polishing device with its axis of rotation in true axial alignment with the axis of the crank pin; to provide for supporting the polishing assembly between spring arms which are adjustable toward and from each other in order to accommodate the polishing elements carried by them to crank pins of different sizes; to provide for the abrasive elements an improved holding means which automatically adjusts itself to the surface of the crank pin; and to provide for the supporting of the polishing elements in such a manner as to afford to the operator a practically unobstructed view of the surface of the

crank pin being polished so that he will know when the polishing operation is complete.

Other objects, advantages and features of invention will hereinafter appear.

5 Referring to the accompanying drawing, which illustrates what is at present deemed to be a preferred embodiment of the invention,

Fig. 1 is a view, partly in side elevation and partly in vertical midsection, showing the device 10 in its operative polishing relation to a locomotive crank pin, a portion of the latter being broken away to contract the view. Also, a fragment only of the driving means is shown, being phantomally indicated by broken lines.

15 Fig. 2 is a section on line 2—2 of Fig. 1.

Fig. 3 is a section on an enlarged scale, the plane of section being indicated on Fig. 1 by the angular line 3—3.

20 Fig. 4 is a fragmental perspective, on the same scale as Fig. 3, wherein is shown a part of the means for attaching a strip of abrasive material to the device.

Fig. 5 is a fragmental perspective, on the same scale as Fig. 3, to afford additional illustration 25 of a detail of the means for clamping in place the forward end of each abrasive strip.

Referring in detail to the drawing, and more particularly to Fig. 1, the tubular body 7 carries at its driven end a spindle-like extension 8, having at its outer end a conventional, flattened key, whereby the polisher is driven by the driving member 10 of a compressed air motor. Said tubular body 7 carries at its inner end, preferably integral therewith, a head consisting of a 30 circular web 11 surrounded by an annular rim 12.

In Figs. 1 and 3 the device is shown in its operative relation to a locomotive crank pin 15 which has the usual diametrically contracted axial end portion 16. In axial alignment with 40 said crank pin is shown a guide bar 17 which has welded to its inner end a cup-shaped head or socket portion 18 fitted over the crank pin extension or contracted end portion 16 and removably secured thereto by a set screw 19. The diameter of said guide bar 17 is somewhat less than the internal diameter of the tubular body 7 and said guide bar is axially held therein in a working fit relation thereto by means of a sleeve or bushing 20.

45 To diametrically opposite sides of the rim 12 are welded or otherwise secured end portions of oppositely disposed spring metal arms 21, each of these arms carrying one member of a pair of 50 arcuate frame members 22 which cooperate to

form opposite side portions of an annular frame to surround the crank pin to be polished.

Each of two attaching bolts 25 has an outwardly projecting portion around which is coiled a compression spring 26 surmounted by a washer 27 against which bears a nut 28 screwed onto said bolt. Through the midwidth portion of each arcuate frame member 22 at its midlength extends a bolt hole 30 through which one of said bolts 25 passes with a clearance therearound. Also, an arcuated countersink 31 is formed in the convex side of the frame member 22, in a concentric relation to the bolt hole 30, within which seats the convex side of a planoconvex ball joint ring 32 and said frame member 22 has a pair of external guide ears 33 located adjacent to opposite sides of the spring arm 21, to limit the lateral movement of the parts carried by said spring arm in relation thereto. By the construction which has just been described each arcuate frame member 22 is fastened in a secure but somewhat flexible manner to the arm 21 by which it is carried, and by substantially a ball joint connection which provides for a slight universal movement of each arcuate frame piece 22 in relation to its supporting arm 21.

Each of the twin arcuate frame pieces 22 extends through considerably less than a semicircle and has at each end a radially projecting apertured ear 35, thus providing for passing bolts 36 through the oppositely disposed ears at each side of the applied device. A compression spring 37 is coiled around that portion of each of these bolts which bridges the gap between the ears at its side of the device. In Fig. 3 the bolt 36 at the right side of the device is shown with its head directed upwardly and the bolt at the left side with its head directed downwardly, in each case the inner side of the head of the bolt abutting against the outer side of one of the ears. Also, each bolt has a screwthreaded end portion which projects a considerable distance beyond that ear which is farthest from the head of the bolt, and this projecting portion of the bolt is surrounded by a compression spring 38, against the outer end of which abuts a washer 39 which is urged against the spring by means of a tensioning nut 40.

The arrangement of bolts and springs which has been described maintains the two arcuate frame pieces 22 in an adjustably tensioned and cushioned relation to the crank pin being operated upon, so that the polishing and abrading means carried by said frame pieces are yieldingly applied to the crank pin under the desired predetermined pressures.

Emery cloth strips 41 mounted in an interiorly spaced parallel relation to the frame pieces 22 may be utilized as polishing elements. Two of these strips are shown each having at one end an outwardly directed end portion 42 which is gripped between blocks 43 and 44. Into the block 43 is screwed a short cap screw 45, and into the block 44 screws a like cap screw 46, short slots 47 and 48, which extend lengthwise of the frame pieces, being provided for the respective cap screws 45 and 46. A washer 49 is shown underlying the head of each cap screw 46.

Adjacent to the slot 48 the end portion of each frame piece 22 has an interior projection 50 provided with a beveled face 51 against which a correspondingly beveled end of block 44 is abuttable. The blocks 43 and 44 are made slightly arcuate as to their lengths and respectively have ribs 52, 53 along the midwidth of their outer faces, these ribs fitting slidably within a longitudinal groove

54 along the midwidth of the concave face of each frame piece 22.

Corresponding to the adjustable block 43 a like adjustable block 55 having a rib 56 is mounted near the opposite end of each frame piece 22, the latter block having screwed into it a cap screw 56 which passes through a slot 57 in the frame piece. The ribbed blocks which have been described are all of the same thickness and hence said blocks 43 and 55 form a plurality of suitable shoes or backing members for the strips 41 of emery cloth and aid in keeping said strips in their proper operative positions. In putting these emery cloth strips in place the short end block 44 of each strip should be put in place last, the adjacent block 43 having previously been mounted in such a position that when the cap screw 46 of the block 44 is screwed down it will cause the beveled face 51 of the projection 50 to bind the block 44 forcibly against the emery cloth end 42 which intervenes between this block and the block 43, thus holding said strip firmly in place with its trailing end portion underlying a block 55, it being understood that the device as viewed in Fig. 3 will be rotated in the clockwise direction.

The aforesaid blocks or shoes 43, 44 and 55 are desirably made of brass, the two blocks 55 being shown of the same size and shape as said blocks 43.

Preparatory to placing the polisher in its operative position the cup-shaped head 18 of the guide bar 17 is placed upon the crank pin extension 16 and is secured thereto by screwing down the set screw 19. Thereupon, assuming that the polishing and/or abrading elements have previously been mounted within the annular frame which has been described, the tubular portion 7 of the polisher will be telescoped over said guide bar 17, thus bringing the device into its operative relation to the crank pin, as illustrated in Fig. 1. After this has been done the socketted driving member 10 of the compressed air motor is applied to the tapered extension 8 and key 9 of the tubular part 7, whereupon said motor is started. It is to be understood that the motor is of a conventional type and is of a light compact structure, which enables the operator manually to move the motor together with the rotating polisher back and forth in the direction of the axis of the crank pin, thereby causing the polishing and/or abrading elements to act upon all parts of the crank pin uniformly until the smoothing and polishing operation has been properly completed. The operator can readily watch the progress of the polishing or abrading operations as the rotating spring arms 21 will not materially obstruct his view of the surface of the crank pin.

It is to be understood that the operator from time to time will apply oil to the polishing and abrading elements as may be necessary to secure the proper finish to the polishing operation. Also the adjusting nuts 40 will be screwed down to the extent necessary to cause the abrading or polishing elements to be applied to the surface of the crank pin under the proper pressures.

The spring action of the resilient arms 21 combined with the action of the cushioning springs 37 causes the annular frame which includes the arcuate frame pieces 22 to expand when said nuts 40 are released. This expansion is necessary, after a polishing operation has been completed, in order to enable the operator to remove the polisher from one crank pin preparatory to placing it upon the next crank pin to be polished.

It should be understood that the present dis-

closure is for the purpose of illustration only and that this invention includes all modifications and equivalents which fall within the scope of the subject matter claimed.

What is claimed is:

1. In a crank pin polishing device, a guide bar having a cup-shaped head secured axially to the diametrically contracted end portion of a locomotive crank pin, an annular frame including a pair of arcuate members which form diametrically opposite side portions of said frame rotatably and slidably mounted on said guide bar, the end portions of said arcuate members being spaced apart from each other at each side of said frame, means mounted on said frame to yieldingly urge said spaced apart end portions of said arms toward each other, and polishing means carried interiorly by said annular frame.

2. In a crank pin polishing device, an annular frame including a pair of arcuate members which form diametrically opposite side portions of said frame, the end portions of said arcuate members being spaced apart from each other at each side of said frame and provided with radially projecting ears, yieldable means bridging the spaces between said ears, means mounted on said ears to yieldingly urge said spaced apart end portions of said arcuate members toward each other against the opposition of said yieldable bridging means, polishing means carried interiorly by said annular frame, said polishing means including a strip of polishing material having a detached trailing end portion to contact the crank pin and an end portion securable interiorly to said frame, and means carried by said frame to overlie the trailing portion of said strip against the crank pin.

3. In a crank pin polishing device, an annular frame including a pair of arcuate members which form diametrically opposite side portions of said frame, the end portions of said arcuate members being spaced apart from each other at each side of said frame, bolts extending through said end portions and bridging the spaces between them, a cushioning spring mounted upon each of said bolts between said spaced apart end portions, another spring mounted upon each of said bolts to yieldingly urge said spaced apart end portions toward each other in opposition to said cushioning springs, and polishing means carried interiorly by said annular frame.

4. In a crank pin polishing device, an annular frame including a pair of arcuate members which form diametrically opposite side portions of said frame, each of said arcuate members having at each end an apertured ear directed radially outward therefrom, the ears at each side of said frame being spaced apart from each other when the device is in its operative position, a bolt passing through the apertures of said spaced apart ears at each side of said frame and bridging the space between them, the head of said bolt engaging the outer side of one of said ears, the end portion of said bolt opposite to its head projecting through and beyond the other of said ears, a coiled compression spring surrounding the portion of said bolt between said ears and serving as a cushion, a coil spring surrounding that portion of said bolt which projects beyond the other of said ears, a nut screwing onto said bolt beyond the latter spring to regulate the tension thereof in opposition to said cushioning spring, and means to connect said annular frame with a driving means for rotation about its axis.

5. In a crank pin polishing device, an annular frame including a pair of arcuate members which

form diametrically opposite side portions of said frame, the end portions of said arcuate members being spaced apart from each other at each side of said frame, yieldable means to maintain the spaced apart relation of said end portions by bridging the spaces between them, means yieldingly connecting said spaced apart end portions to each other at each side of said frame, means carried interiorly by each of said arcuate members to detachably secure an end portion of a strip of abrading material thereto with the remainder of said strip in a position to be trailed over the surface of the crank pin being polished when the device is in its operative position, a backing member for the trailing portion of said strip, said backing member also being carried interiorly by said arcuate member, and means to rotationally connect said annular frame to a driving means in a surrounding relation to a locomotive crank pin.

6. The subject matter of claim 5, and said means for attaching the abrading strip including two abuttable blocks at least one of which is adjustably supported upon the interior face of said arcuate member in relation to the other block, and means for releasably securing said one of said blocks to said arcuate member in a position for gripping between them a deflected portion of said abrading strip.

7. In a crank pin polishing device, an annular frame including a pair of arcuate members which form diametrically opposite side portions thereof, the end portions of said arcuate members being spaced apart from each other at opposite sides of said frame, resilient means carried by said spaced apart end portions to adjustably maintain them in their spaced apart relation to each other, each of said arcuate members having a bolt hole through it at substantially its midlength and an arcuate countersink in its convex side around said bolt hole, a plano-convex washer having its convex face seated in said countersink, means to rotate said frame about its axis, said last recited means carrying a pair of parallel spaced apart arms each of which extends in an overlying adjacent relation to one of said countersunk bolt holes, a bolt passing through each of said arms, bolt holes and washers and having a head engaging the concave side of the arcuate member provided therewith, a spring surrounding said bolt and abutting against the outer side of said arm, a nut screwing onto said bolt in an abutting relation to the outer end of said spring, said bolt being of materially less diameter than said bolt hole thus allowing a slight universal movement of the aforesaid annular frame in relation to said arms by and between which it is supported, and polishing elements mounted upon said annular frame in an interior relation thereto.

8. In a device of the kind described, a guide bar, a cup-shaped head the bottom of which is secured axially to one end of said guide bar with the mouth of the cup located outwardly beyond said end of the bar for securing axially to the diametrically contracted end portion of a locomotive crank pin, a tubular body rotatably and slidably mountable on said guide bar, said body having an axial extension at one end for connection with a manually supportable driving means, a head concentrically fixed to said tubular body at its opposite end, a pair of arms each having an end portion fixed to said head, an annular frame having diametrically opposite side portions one of which is secured to one of said arms and the other of which is secured to the other arm, and crank

pin polishing means carried interiorly by said annular frame.

9. The subject matter of claim 8, and said arms of said pair being resilient and said annular frame being diametrically expandable to vary the distance between its said side portions to facilitate the application of said polishing means to and their removal from locomotive crank pins, a plano-convex ball joint ring between said annular frame and each of said arms, there being an arcuated countersink formed in the convex side of said frame in which the convex side of each of said plano-convex ball joint rings seat, and means for yieldingly securing each said arm and plano-convex ball joint ring to said frame.

10. The subject matter of claim 8 and, cushioning means interposed and bridging the space between the end of said diametrically opposite side portions of said annular frame, and resilient means including a bolt and nut construction loosely carried by said end of said diametrically opposite side portions and adjustable to contract the spaces between them varying amounts against the opposition of said cushioning means, the heads of said bolts engaging alternate ends of said opposite side portions.

11. In a crank pin polisher, a tubular body, means carried by one end portion of said body for connecting it with a driving means for rotation about its axis, a pair of diametrically opposite, spaced apart arms extending parallel to the axis of said body, means whereby said arms are secured to that end of said tubular body which is opposite to the end thereof which is attachable to said driving means, a frame of an annular character to include within it a crank pin to be polished, means carried by opposite side portions of said frame and located exteriorly thereof to attach said frame to said arms in a position wherein it bridges the space between them, polishing means mounted upon and interiorly of said annular frame, and a ball joint connection between said annular frame and each of said arms.

12. In a crank pin polishing device, an annular frame including a pair of arcuate members which form diametrically opposite side portions of said frame, the end portions of said arcuate members being spaced apart from each other at each side of said frame, means yieldingly connecting said spaced apart end portions to each other at each side of said frame, means carried interiorly by each of said arcuate members to detachably secure an end portion of a strip of abrading material thereto with the remainder of said strip in a position to be trailed over the surface of the crank pin being polished when the device is in its operative position, a backing member for the trailing portion of said strip, said backing member also being carried interiorly by said arcuate member, means to rotationally connect said annular frame to a driving means in a surrounding relation to a locomotive crank pin, said means for attaching the abrading strip including two abuttable members carried interiorly by said arcuate member at different points along the length thereof, said arcuate member having an internal projection provided with a bevel and one of said abuttable members consisting of a block which is abuttable against said bevel at one side, and a cap screw projecting through said arcuate member from its convex side and threaded into said block to draw the latter against said bevel and thus shift the block toward the other member against which it is abuttable to grip a part of the abrading strip.

13. In a crank pin polishing device, an annular frame including a pair of arcuate members which form diametrically opposite side portions of said frame, each of said arcuate members having at each end an apertured ear directed radially outward therefrom, the ears at each side of said frame being spaced apart from each other when the device is in its operative position, a bolt passing loosely through the apertures of said spaced apart ears at each side of said frame and bridging the space between them, the head of said bolt engaging the outer side of alternate ears, the end portion of said bolt opposite to its head projecting through and beyond the other of said ears, and a coiled compression spring surrounding the portion of said bolt between said ears and serving as a cushion.

14. In a crank pin polishing device, an annular frame including a pair of arcuate members which form diametrically opposite side portions of said frame, the end portions of said arcuate members being spaced apart from each other at each side of said frame, connecting means extending through said end portions and bridging the spaces between them, a cushioning spring mounted upon said connecting means between each of said spaced apart end portions, another spring mounted upon said connecting means to yieldingly urge each of said spaced apart end portions toward each other in opposition to said cushioning springs, and polishing means carried interiorly by said annular frame.

15. In a crank pin polishing device, an annular frame including a pair of arcuate members which form diametrically opposite side portions of said frame, the end portions of said arcuate members being spaced apart from each other at one side of said frame, connecting means extending through said spaced apart end portions and bridging the space between them, a cushioning spring mounted upon said connecting means between said spaced apart end portions, another spring mounted upon said connecting means to yieldingly urge said spaced apart end portions toward each other in opposition to said cushioning spring, means connecting the end portions of said arcuate members on the side thereof which is opposite said connecting means, and polishing means carried interiorly by said annular frame.

16. In a crank pin polishing device, an annular frame including a pair of arcuate members which form diametrically opposite side portions of said frame, each of said arcuate members having at each end an apertured ear directed radially outward therefrom, the ears at each side of said frame being spaced apart from each other when the device is in its operative position, a bolt passing through the apertures of said spaced apart ears at each side of said frame and bridging the space between them, the head of said bolt engaging the outer side of one of said ears, the end portion of said bolt opposite to its head projecting through and beyond the other of said ears, a coiled compression spring surrounding the portion of said bolt between said ears and serving as a cushion, and a coil spring surrounding that portion of said bolt which projects beyond the other of said ears.

17. In a crank pin polishing device, an annular frame including a pair of arcuate members which form diametrically opposite side portions of said frame, each of said arcuate members having at each end an apertured ear directed radially outward therefrom, the ears at each

side of said frame being spaced apart from each other when the device is in its operative position, a bolt passing through the apertures of said spaced apart ears at each side of said frame and bridging the space between them, the head of said bolt engaging the outer side of one of said ears, the end portion of said bolt opposite to its head projecting through and beyond the other of said ears, a coiled compression spring surrounding the portion of said bolt between said ears and serving as a cushion, a coil spring surrounding that portion of said bolt which projects beyond the other of said ears, and a nut screwing onto said bolt beyond the latter spring to regulate the tension thereof in opposition to said cushioning spring, and means to connect said annular frame with a driving means for rotation about its axis.

18. In a crank pin polishing device, an annular frame including a pair of arcuate members which form diametrically opposite side portions of said frame, each of said arcuate members having at each end an apertured ear directed radially outward therefrom, the ears at each side of said frame being spaced apart from each other when the device is in its operative position, a bolt passing through the apertures of said spaced apart ears at each side of said frame and bridging the space between them, the head of said bolt engaging the outer side of one of said ears, the end portion of said bolt opposite to its head projecting through and beyond the other of said ears, a coiled compression spring sur-

rounding the portion of said bolt between said ears and serving as a cushion, a coil spring surrounding that portion of said bolt which projects beyond the other of said ears, and a nut screwing onto said bolt beyond the latter spring to regulate the tension thereof in opposition to said cushioning spring.

19. In a crank pin polishing device, an annular frame including a pair of arcuate members which form diametrically opposite side portions of said frame, the end portions of said arcuate members being spaced apart from each other at each side of said frame, connecting means extending through said end portions and bridging the spaces between them, a cushioning spring mounted upon said connecting means between each of said spaced apart end portions, another spring mounted upon said connecting means at one side of said frame to yieldingly urge said spaced apart end portions at that side of the frame toward each other in opposition to its cushioning spring, and polishing means carried interiorly by said annular frame.

20. The subject matter of claim 14, and said second said springs being mounted upon the outer, alternate faces of said spaced apart end portions.

21. The subject matter of claim 4, and the bolt at one side of said frame being directed upwardly and the bolt at the opposite of said frame being directed downwardly.

HENRY E. KLINGLESMITH.
